ALBERT BROWN, OF ROCHESTER, NEW YORK, ASSIGNOR TO VOGT MANUFACTURING CORPORATION, OF ROCHESTER, NEW YORK, A CORPORATION OF NEW YORK

PULL CORD OR THE LIKE

Application filed December 24, 1928. Serial No. 328,249.

My present invention relates to cordage and more particularly to pull cords of the nature used, for instance, in the interior fittings of automobile bodies to provide grips whereby passengers may steady themselves in their seats, and the invention has for its object to provide a decorative and yet strong and durable pull cord of this character, though it may be utilized in the making of tassels, ropes, or hangings of all kinds.

To these and other ends the invention resides in certain improvements and combinations of parts, all as will be hereinafter more fully described, the novel features being pointed out in the claims at the end of this specification.

In the drawing:

Fig. 1 is a front view centrally broken away of a pull cord fitting for automobiles constructed in accordance with and illustrating one embodiment of my invention;

Fig. 2 is a longitudinal central section through a portion of the machine for making the tassel portion or grip of the pull cord;

Fig. 3 is an enlarged view of a number of tassel parts as they appear in Fig. 2, showing the manner in which the tie piece is applied to each;

Fig. 4 is an enlarged view of one of the tie wires;

Fig. 5 is an enlarged section through one of the tassels adjacent to the plane of the tie wire, and

Fig. 6 is a similar section to that of Fig. 5 showing the mode of attachment to the end of the body cord.

Similar reference numerals throughout the several views indicate the same parts.

A pull cord of the kind mentioned and as shown in Fig. 1 comprises an attaching plate A having a ring portion B secured in sliding engagement with a shank portion or body cord C. At the lower end of the latter is a tassel D which, in connection with a collar E surrounding the cord constitutes the hand grip that is grasped by the passenger. It is obvious that a great strain is imposed upon the latter part or parts and great difficulty has hitherto been had in at-

taching them so securely to the cord C that they will not break or pull off.

Although a preferred method of constructing the pull cord constituting the subject matter of this invention is a separate subject matter of invention, I will explain the same in connection with this description to give a better understanding of my product, and referring to Fig. 2, on this understanding, I preferably form my tassels or pull cords in the following manner:

Strands of yarn 1 supplied from spools 2 are run through a tube 3 which forms them into a uniform untwisted rope 4. The rope preferably has an intermittent feed and as it emerges from the opposite end of the tube, I tie it tightly at intervals to form a plurality of restricted portions 5 alternating with relatively expanded portions 6. The tying means that I use is preferably in the form of a bent wire eye 7 having end portions 8, as shown in Fig. 4. The eye is slipped over the rope 4 and twisted tightly as shown in Fig. 3. Preferably with the use of a sharp revolving knife I then sever each expanded portion 6 at the center so that the wire tie piece comes off with half of one substantially spherical expanding portion on each side. These are then fluffed up and trimmed to the spherical form shown at D in Figs. 1 and 6, making a soft but dense ball, from which protrudes the legs 8 of the tie wire as indicated in Fig. 5. The trimming is done by hand or machine as preferred, in a well known manner.

To fasten the tassel D thus formed to the cord or body C, I drive the end portions 8 of the tie wire centrally into the end of the cord. I then bind the latter tightly with another wire 9 after which I bend the end portions 8 back upon themselves on the outside of the cord after passing them laterally through the same to form hooks or prongs 10. Previously to this there has been slipped over the cord the collar E which is preferably composed of a turned wood center 11 and a fabric covering 12 therefor. This collar is now drawn down against and partially into the tassel D, as shown in Figs. 1 and 6. It covers and conceals the wires 7, 8, 9, and the

prongs 10 having been originally sprung beyond the interior diameter of the collar are compressed so that they are under expanding tension. This causes them to dig into the 5 interior wooden walls of the collar and hold it tightly in place, particularly against a return movement loosening it from the tassel. A very strong and durable pull cord grip is thus produced which it is practically 10 impossible to pull apart even with the entire weight of the passenger upon it.

As before stated, my invention is not restricted to pull cords alone, although the strength of the construction strongly recommends it to this application. It will be seen 15 by those skilled in the art that features of the invention may be employed wherever a tuft or tassel is to be applied to the end of a cord or hanging, whether for decorative 20 or utilitarian purposes.

I claim as my invention:

1. In a pull cord, the combination with a rope body portion or shank, of a gripping tassel embodying yarns fashioned into a ball 25 held gripped at its center within a wire loop, the ends of the wire being driven into the body portion to secure the tassel thereto. 30 2. In a pull cord, the combination with a rope body portion or shank, of a gripping tassel embodying yarns fashioned into a ball held gripped at its center within a wire loop, the ends of the wire being driven into the body portion to secure the tassel thereto and turned backward to form prongs, and a collar 35 constituting part of the grip held in place by the prongs.

3. In a pull cord, the combination with a rope body portion or shank, of a gripping tassel embodying yarns fashioned into a ball 40 held gripped at its center within a wire loop, the ends of the wire being driven into the body portion to secure the tassel thereto, and turned backward to form prongs, a clinching element surrounding the body portion 45 under the prongs, and a collar constituting part of the grip held in place by the prongs.

4. In combination, a terminal member, a flexible support therefor, a clamp embracing said support, and a metallic connecting member 50 having a portion engaging said terminal member and having its free ends interlocking with said clamp to retain said terminal member engagement with an end of said support.

5. In combination, a pompon, a flexible support therefor, a ring embracing said support adjacent to one end, a second ring embracing said support and spaced from said first mentioned ring, and a metallic connecting member 55 having a portion engaging said pompon and having its free ends cooperating with said rings to retain said pompon in engagement with an end of said support.

6. In combination, a pompon, a flexible support therefor, a ring embracing said support adjacent to one end, a second ring embracing 60

said support and spaced from said first mentioned ring, and a metallic connecting member having a portion engaging said pompon and having its free ends interlocking with said second mentioned ring and cooperating 70 with said first mentioned ring to retain said mass in engagement with an end of said support.

7. In combination, a pompon, a flexible support therefor, a ring embracing said support adjacent to one end, a metallic connecting member engaging said pompon and having its free ends interengaging with portions 75 of said ring and a ferrule embracing said support and positioned to retain said ends in 80 operative ring engaging position.

8. In combination, a pompon, a support therefor, a ring embracing said support, a yoke shaped connecting member positioned with a portion of its bight engaging the pompon and its free ends extending through said ring, said ends being bent back upon themselves. 85
